UNITED STATES PATENT OFFICE.

ANDERS RASMUSSEN, OF NEW ALBANY, INDIANA.

CREW-SAVING DEVICE FOR SUBMARINES.

Application filed April 21, 1927. Serial No. 185,625.

This invention relates to new and useful improvements in life saving devices and has more particular reference to an apparatus constructed for association with a submarine 5 to enable the crew to escape therefrom in the event the submarine cannot arise to the surface of the water.

In carrying out my invention there is provided a plurality of similarly constructed 10 human body containers for receiving the various members of the crew, which containers will immediately rise to the surface of the water when ejected from the submarine and float thereon in a manner of a 15 small boat, means being provided whereby the said containers may be ejected from the submarine and this with little or no liability of the water entering the compartment containing the mechanism.

20 The most important object of the present invention other than for the purpose for which it is provided is to permit the mechanism to be associated with all designs of submarines now in use and this without great 25 expenditure and without materially adding to the cost of construction of new submarines equipped with such device.

In the drawings wherein like reference 30 characters indicate corresponding parts throughout the several views:

Figure 1 is a fragmentary longitudinal section of a submarine equipped with my improved apparatus.

Figure 2 is a detail longitudinal section 35 through the guide tube for the human containers, the outer end thereof being plugged to prevent the entrance of water into the submarine.

Figure 3 is a similar view, the plug being 40 removed and a pair of the human containers being disclosed as arranged therein.

Figure 4 is a detail longitudinal section 45 through one of the containers, per se.

Figure 5 is a transverse section through the container taken substantially upon the line 5—5 of Figure 4, and

Figure 6 is an enlarged fragmentary section 50 through the container for more clearly disclosing the construction of a small door conveniently located therein, whereby the occupant may reach therethrough for controlling the ejecting mechanism in the event he is the last of the crew to depart from the submarine.

55 Now having particular reference to the drawing A in Figure 1 designates frag-

mentary a submarine that is constructed at any convenient point throughout its length and at the top side with a compartment *a*. Arranged diagonally within this compartment *a* and having one end projecting through the top of the submarine is a cylindrical tube 5 open at its outer end as clearly indicated in Figure 2. Any desirable supporting means may be provided for this tube, 60 and in so much as this is not an essential feature of the invention no particular means is disclosed. Said tube 5 at the outer end thereof is provided with an internal channel 6 within which is normally arranged a closure 65 plug 7 to prevent the inlet of the water into the tube and consequently into the compartment *a*. When submerged the pressure of the water against this plug will serve to maintain the same in place. However, any 70 suitable means may be provided for securing the same against accidental displacement 75 within the tube.

As clearly disclosed in Figures 2 and 3 the top side of the tube at its rear end is formed 80 with a semi-circular and horizontally extending cut out 8 to permit the human containers, hereinafter more fully described, to be disposed horizontally therein and to permit the crew to enter the containers after 85 the same have been arranged in said tube.

These containers more clearly disclosed in Figures 3, 4, 5 and 6 are preferably of elongated cylindrical formation and designated by the reference character 9, the front end of 90 each container being preferably rounded as clearly disclosed in Figures 3 and 4. Adjacent their forward and rear ends, said containers are formed with circumferential ribs 10 for tightly engaging the interior of the 95 tube 5 to prevent the passage of water between said containers and said tube, when the same are projected forwardly beyond the cut out 8 as indicated in Figure 3. These containers are provided at their forward ends 100 in each instance with a horizontal partition 11 so that provision and panel compartments are provided. Furthermore, each container 11 is equipped at its bottom side with a pivotal blade 12 that is normally arranged with 105 in a horizontal pocket 13 in the bottom side thereof, these blades being provided for stabilizing the containers after the same have reached the surface of the water and in order 110 that the said containers may be paddled from place to place without any liability of the same rolling over.

Between the circumferential ribs 10—10 each container is provided at its top side with a door opening 14. Hingedly attached to the opposite longitudinal edges of this door opening are door sections 15—15 hinged to the container to swing outwardly as indicated in Figure 5. The edges of the door opening and the adjacent edges of the door sections are formed to provide water proof joints 16—16. Furthermore the adjacent edges of these sections are constructed to have overlapping relation and furthermore to provide a water proof joint 17. At the ends of the door opening 14 the interior of each container 9 is formed with depending and inwardly extending tongues 18—18 slotted at their inner ends for receiving bolts 19—19 pivotally attached to the under side of the door section whose free edge overlaps the free edge of the adjacent door section, and upon which bolts are arranged hand turning nuts 20—20 so that the doors may be locked in closed condition.

As indicated in Figures 3 and 6, one side of each container adjacent the opening 14 is provided with a small opening 21 to one edge of which is hingedly secured a door 22 in such a manner as to swing inwardly in the direction of the arrow in said Figure 6. The edges of the door and opening are formed to provide water tight joints as clearly indicated. Furthermore, a suitable locking means 22 is provided for facilitating the rigid securing of the door in closed position, such locking means being preferably that as previously described for locking the door sections 15—15 in closed position. This door is provided in order that the last member of the crew to depart may reach there through and start the container ejecting mechanism hereinafter more fully described.

In the actual operation of an apparatus of this character, one container 9 is first arranged within the opening 8 of the tube 45 5 and thence forced forwardly to the position indicated in Figure 3, the forward movement of the same projecting the plug 7 from the outer end of the tube. However, the position of the container within the tube 50 will prevent the passage of water into the submarine as previously described. For maintaining the first container in position partially projected through the forward end of the tube, a suitable spring latch 23 is associated with the bottom of the tube, the latch pin thereof projecting into the tube and being tapered as indicated in said Figure 3 so as to permit the container to be forcibly moved forwardly. After the first container 60 is arranged within the forward end of the tube a second container is disposed therein after which the mechanism is set into operation for forcing the rearmost tube forwardly which tube will in turn contact the forward 65 tube for expelling the same from the tube

whereupon it will rapidly rise to the surface of the water, it being understood that after each container is disposed within the tube the door sections 15—15 are opened, and one member of the crew enters therein.

One means whereby the container may be expelled from the tube is herein shown and described. However, it is to be understood that I do not desire to be limited to any such mechanism as other means may be provided without affecting the spirit and scope of the present invention. The means disclosed consists of a bar 24, the forward end of which is arranged through an opening in the rear wall of the tube 5 and headed as at 25 for engaging a socket 26 in the rear end of the various containers 9. This bar 24 is provided with a rack 26 having mesh with a gear 27 operated by any mechanism desired, but preferably of an electrical nature and this is such that the same will not operate immediately upon the turning on of the switch, so that the last member of the crew may reach through the side door and turn the switch on. Furthermore, the mechanism should be such that it can be set for causing a long or short stroke of the said plunger bar order that the last container within the tube may be shoved entirely there through as will be necessary.

It will thus be seen that I have provided a highly novel, simple and efficient mechanism whereby the crew of a submarine may be brought to the surface of the water and even though I have herein shown and described the apparatus as consisting of certain detail structural elements it is nevertheless to be understood that I do not desire to be limited to such a disclosure for the reason that numerous departures may be made therefrom without affecting the spirit and scope of the appended claims.

Having thus described the invention, what I claim is:—

1. In a crew saving device for submarines, a relatively elongated tube open at its outer end and arranged at its said open end through the outer wall of the submarine, a closure plug normally arranged within the outer open end of the tube, a floatable human container for disposition within the tube, means for ejecting the container from said tube whereupon it will float to the surface of the water, said tube being of such length as to receive two of the containers, the rearmost container adapted to project the outermost 115 container from the tube and to plug the interior of the tube so as to prevent the passage of water between the tube and said container.

2. In a crew saving device for submarines, a relatively elongated tube open at its outer end and arranged at its said open end through the outer wall of the submarine, a closure plug normally arranged within the outer open end of the tube, a floatable human 120

container for disposition within the tube, means for ejecting the container from said tube whereupon it will float to the surface of the water, said tube being of such length as to receive two of the containers, the rearmost container adapted to project the outermost container from the tube and to plug the interior of the tube so as to prevent the passage of water between the tube and said container, and means associated with the tube for preventing the inward movement of the outermost container after the same has been partially projected from said tube.

3. In a crew saving device for submarines, a tube arranged within the submarine open at one end and arranged at said open end

through the deck of the submarine, a plug normally closing the open end of the tube, a plurality of floatable human containers for disposition within the tubes said tube being of a length to accommodate a pair of said human containers in longitudinal alignment, and means for engaging the rearmost container to force the same longitudinally outwardly within the tube to a point projecting slightly beyond the open end of the tube, said rearmost container adapted to force the outer container entirely outward of the tube whereupon it will rise to the surface of the water.

In testimony whereof I affix my signature.

ANDERS RASMUSSEN.
